UNITED STATES PATENT OFFICE.

CYRUS C. JOHNSON, OF MOUNT VERNON, ILLINOIS.

OIL-BURNER.

Specification of Letters Patent. Patented June 23, 1914.

1,100,889.

Application filed January 8, 1914. Serial No. 811,068.

To whom it may concern:

Be it known that I, CYRUS C. JOHNSON, a citizen of the United States, residing at Mount Vernon, in the county of Jefferson and State of Illinois, have invented a new and useful Oil-Burner, of which the following is a specification.

The present invention appertains to oil stoves or heaters, and aims to provide a novel and improved device of that character.

It is the object of the present invention to provide an oil stove comprising a unique structure, and arranged to efficiently burn crude oil or other liquid fuel, with a minimum amount of soot.

As a more specific object, the present invention aims to provide an oil stove including a down draft air tube, in connection with combustion supporting means at the lower end of the tube, and means for supplying the liquid fuel to the said means, whereby the inflowing air will direct the flames radially in all directions from the lower end of the down draft tube.

It is also within the spirit of the present invention, to provide an oil stove of comparatively simple, light, and durable as well as inexpensive construction, which shall be simple, practical and efficient in operation.

With the foregoing general objects outlined, and with other objects in view, which will be apparent as the nature of the invention is better understood, the present invention resides in the combination and arrangement of parts and in the details of construction hereinafter described and claimed, it being understood that changes in the precise embodiment of the invention herein disclosed, can be made within the scope of what is claimed, without departing from the spirit of the invention.

The invention has been illustrated in its preferred embodiment in the accompanying drawing, wherein the figure is a central vertical section of the improved oil stove.

In carrying out the present invention, there is provided an upright cylindrical casing 1, which may be of sheet metal, and which has a top or cover 2 attached to its upper end, a stove pipe 3 being connected to the top or cover 2 to carry off the products of combustion from the casing 1. The front of the casing 1 is provided with a door 4 adjoining its lower end, and a bottom 5 and supporting legs 6 are attached to the lower end of the casing, the bottom 5 as well as the

legs 6 being preferably, although not necessarily, of cast metal.

The bottom 5, which forms an essential feature of the present invention, has its central portion raised, or conical in form, as at 7, and has an annular depression 8 formed adjoining its margin or periphery, or between the raised or conical portion 7 and the rim or periphery of the bottom. Upon the apical portion of the bottom, is disposed a circular or disk-like pad or wick 9 of asbestos or similar material having absorbent properties. An angular down draft tube 10 is disposed within the casing 1 and has one arm or end attached to the back of the casing 1 to communicate therethrough, while the other or free arm of the tube 10 depends and terminates adjoining, but slightly spaced from, the pad or wick 9.

The fuel tank 11 is supported from the back of the stove casing 1, by means of a pair of arms 12 secured to the back of the casing above the inlet end of the down draft air tube 10, and formed with bands 13 at 80 their free ends embracing the tank 11. A liquid fuel pipe 14 is attached to the bottom or lower end of the tank 11 and extends axially through the upper or horizontal arm of the down draft tube 10, the free end or 85 nozzle 15 of the pipe 14 being bent angularly downward within the depending or vertical arm of the tube 10. The pipe 14 is provided with a needle or other valve 16 for controlling the passage of fuel therethrough 90 from the tank 11. A second liquid fuel pipe 17 is connected to the bottom or lower end of the fuel tank 11, and extends below the stove casing 1, the free end or nozzle 18 of the pipe 17 being engaged upwardly through the apex of the bottom 5 and through the wick 9. The pipe 17 is provided with a needle valve 19 for controlling the flow of fuel therethrough. A baffle plate 20 is bolted or otherwise secured to the legs 6 between 100 their lower ends and the bottom 5 of the stove casing, to direct the downwardly radiated heat toward the several sides, and to prevent the downwardly radiated heat from reaching or attacking the floor.

In operation, either of the liquid fuel supply pipes 14 or 17 may be opened, to supply the fuel to the wick 9 drop by drop. As soon as sufficient fuel is absorbed by the wick 9, the wick may be lighted, by opening the door 4, which will start the combustion, the air flowing downwardly through the down

draft tube 10 and in escaping from the lower end of the down draft tube, will direct the flames radially, the flames then rising along the walls of the casing 1. In this manner, a uniform heat is established around the stove, and the heat will also be radiated downwardly from the bottom of the stove, which is highly desirable. The air being drawn into the down draft tube 10, will create a current of air around the fuel tank 11, whereby the said fuel tank will be cooled, or prevented from heating. The wick 9 being carried by the apex of the bottom, and the bottom being provided with the annular depression 8, will permit the flames to properly issue radially from the wick 9, without burning the bottom, it being observed that the heat will be radiated downwardly through the bottom of the stove casing. Particular attention is directed to the fact that the lower end of the down draft tube terminates adjacent the apex of the raised portion of the bottom, there being only a slight space between the wick and the down draft tube, whereby the air passing from the lower end of the down draft tube, will contact with and tend to penetrate the wick, to assist in the vaporization of the fuel in an effective manner. The baffle plate 20 prevents the downwardly radiated heat from reaching the floor, that is, directly from the bottom of the stove casing, but directs the said heat laterally. The baffle plate 20 also serves to steady the legs 6, and may serve as a foot rest, whereby the feet may be readily warmed by the downwardly radiated heat.

The present stove or burner will produce a maximum heating effect, with a minimum amount of fuel, and with a minimum amount of soot.

After the combustion has been started, it will be manifest that the fuel will be readily vaporized as it reaches the wick 9. The air

in passing radially from the lower end of the down draft tube 10 is mixed with the 45 vaporized fuel in order that the mixture will burn with a blue or Bunsen flame.

Having thus described the invention, what is claimed as new is:—

1. In a stove, a casing, the bottom of the 50 casing having a central raised portion, and a surrounding annular depression, a down draft tube within the casing and terminating directly above the apex of the said raised portion, and a liquid fuel supply pipe passed 55 upwardly through the apex of the said raised portion.

2. In an oil stove, a casing, the bottom of which has a central raised portion and a surrounding annular depression, a down 60 draft tube within the casing terminating adjacent the apex of the said raised portion, a wick disposed upon the apex of the said raised portion, and means for supplying liquid fuel to the said wick, there being a 65 slight space between the wick and draft tube.

3. In an oil stove, a casing, an angular down draft tube having one arm attached to one wall of the casing and having its other arm depending in the casing, combustion supporting means disposed below the lower end of the said tube, a liquid fuel tank supported from the said wall of the casing adjoining the inlet end of the said 70 tube, and means for conducting the fuel from the tank to the said combustion supporting means.

In testimony that I claim the foregoing as my own, I have hereto affixed my signature in the presence of two witnesses.

CYRUS C. JOHNSON.
